US00D808663S

(12) **United States Design Patent** (10) Patent No.: **US D808,663 S**
(45) Date of Patent: **** Jan. 30, 2018**

(54) **WIPE WITH SURFACE PATTERN**

- (71) Applicant: **FIRST QUALITY TISSUE, LLC**,
Great Neck, NY (US)
- (72) Inventors: **Justin S. Pence**, Anderson, SC (US);
Taras Z. Andrukh, Greenville, SC
(US); **Chris B. Anklam**, Anderson, SC
(US)
- (73) Assignee: **FIRST QUALITY TISSUE, LLC**,
Great Neck, NY (US)
- (**) Term: **15 Years**

(21) Appl. No.: **29/568,420**(22) Filed: **Jun. 17, 2016**

(51) LOC (11) Cl. **05-05**
(52) U.S. Cl. **D5/37**

(57) **CLAIM**

The ornamental design for a wipe with surface pattern, as shown and described.

DESCRIPTION

FIG. 1 is a perspective view of a wipe with surface pattern;
FIG. 2 is a top plan view thereof;
FIG. 3 is a bottom plan view thereof;
FIG. 4 is a left side view thereof;
FIG. 5 is a right side view thereof;
FIG. 6 is a front view thereof; and,
FIG. 7 is a back view thereof.
The broken lines surrounding the drawings depict the boundaries of the claim and form no part thereof.

1 Claim, 5 Drawing Sheets
